UNITED STATES PATENT OFFICE.

LOUISE H. PERCY, OF PHILADELPHIA, PENNSYLVANIA.

WASHBOARD.

No. 906,270.

Specification of Letters Patent.

Patented Dec. 8, 1908.

Application filed December 31, 1907. Serial No. 408,810.

To all whom it may concern:

Be it known that I, LOUISE H. PERCY, a citizen of the United States, and a resident of Philadelphia, in the county of Philadelphia and State of Pennsylvania, have invented a new and Improved Washboard, of which the following is a full, clear, and exact description.

This invention is an improvement in washboards, having in view the provision of means for supporting the board over the tub in a substantially horizontal and slightly depressed position, whereby it will be unnecessary to bend the back in washing, to the extent required as when the board is disposed in the usual manner.

The invention also resides in the board construction which is designed to prevent the splashing by the water on the operator, and is provided with perforated pockets at the sides for retaining such articles as a scrubbing brush and soap.

Reference is to be had to the accompanying drawings forming a part of this specification, in which similar characters of reference indicate corresponding parts in all the views.

Figure 1 is a perspective view illustrating the preferred embodiment of my improved board as applied to a tub; Fig. 2 is a longitudinal section through the same, substantially on the line 2—2 of Fig. 1, Fig. 3 is a similar section on the line 3—3 of Fig. 1; and Fig. 4 is a fragmentary perspective view of the board, showing the corrugated portion 35 made as a separate part.

The board proper is preferably constructed entirely of sheet metal, the same comprising a flat plate 5 having the usual length of transverse corrugations 6 either stamped 40 from the body thereof or made as a separate part and afterward attached, and constructed at its head or forward end with an upwardly and outwardly-curved splash-plate 7. The length and position of the corrugations 45 6 are such as to leave a plain marginal portion 8 at one side, and a similar but somewhat wider portion 8^a at the opposite side; this last-named plain portion of the board being divided into seats or pockets by extending certain of the corrugations there-across and providing the outer edge with an upwardly-turned flange 9. These pockets have perforated bottoms for admitting of the passage of the water therethrough into 55 the tub, and the bottoms of the corrugations are also provided with perforations 10, as

shown in Fig. 3, for a like purpose. At the opposite sides of the board, keepers 11 are secured to the under side thereof near the opposite ends, which receive the shanks of 60 hooks 12, the said shanks being slidably retained in the keepers, whereby the hooks may be adjusted within certain limits on the board. The hooks 12, as best shown in Fig. 1, are off-set to carry them above the top of 65 the board, which construction, when engaged with the top edge of the tub, supports the board over the tub slightly depressed therein, which prevents the water from the board running upon the floor. The board is 70 further engaged with the top edge of the tub by hooks 13, rigidly fixed to its head end, which prevents any sliding or shifting of the board when in use.

The manner of using the board is as follows: The clothes to be washed are spread upon the corrugated portion of the board, and a brush 14, such as illustrated in Fig. 1, is used in scrubbing them; the water running off at the edges of the board and also 80 through the perforations in the bottom thereof. During the use of the brush, the soap may be applied thereto without removing the cake from the soap pocket, which arrangement obviously at all times makes the 85 soap and brush conveniently accessible.

The invention as shown and described while being the preferred manner of arrangement and construction of my improved wash-board is nevertheless susceptible of 90 modifications falling within the scope of the appended claims.

Having thus described my invention, I claim as new and desire to secure by Letters Patent:

1. A wash board having a corrugated portion and provided with pockets at one side of the corrugations, hooks adjustable transversely of the board at opposite sides thereof, adapted to support the board within a 100 tub slightly depressed below its top edge and in an approximately horizontal position, leaving the rear end of the board free and unobstructed, whereby the clothes may be drawn thereover from the tub, and a splash 105 plate connected to the board at its opposite end.

2. A sheet metal wash board having a corrugated portion and provided with perforated pockets at one side of the corrugations, hooks adjustable transversely of the board at opposite sides thereof, hooks rigidly 110

attached to the forward end of the board, said hooks adapted to support the board within a tub, slightly depressed below its top edge and in an approximately horizontal position, and a splash plate integral with the board, curved upwardly and outwardly over the top of the rigidly-attached hooks.

In testimony whereof I have signed my name to this specification in the presence of two subscribing witnesses.

LOUISE H. PERCY.
